Primary Examiner — Susan E Krakower*Assistant Examiner* — Michael A Maharajh*(74) Attorney, Agent, or Firm* — Sven W Hanson(57) **CLAIM**

The ornamental design for a horse self-massage device, as shown and described.

DESCRIPTION

FIG. 1 is a perspective view of a horse self-massage device illustrating the new design.

FIG. 2 is a bottom perspective view thereof.

FIG. 3 is a front elevation view thereof.

FIG. 4 is a back elevation view thereof.

FIG. 5 is a right side elevation view thereof.

FIG. 6 is a left side elevation view thereof.

FIG. 7 is a top plan view thereof; and,

FIG. 8 is bottom plan view thereof.
